(57) **CLAIM**

We claim the ornamental design for a ice auger bit, as shown and described.

DESCRIPTION

FIG. 1 is a perspective view of an ice auger bit showing my new design.

FIG. 2 is a front view of the ice auger bit of FIG. 1.

FIG. 3 is a rear view of the ice auger bit of FIG. 1.

FIG. 4 is a left side view of the ice auger bit of FIG. 1.

FIG. 5 is a right side view of the ice auger bit of FIG. 1.

FIG. 6 is a top view of the ice auger bit of FIG. 1; and,

FIG. 7 is a bottom view of the ice auger bit of FIG. 1. The broken lines in the drawings depict unclaimed environmental subject matter.
